UNITED STATES PATENT OFFICE.

WILLIAM C. BURWELL, OF PROVIDENCE, RHODE ISLAND.

DESIGN FOR A LADLE OR SIMILAR ARTICLE.

SPECIFICATION forming part of Design No. 32,149, dated January 30, 1900.

Application filed January 2, 1900. Serial No. 180. Term of patent 7 years.

To all whom it may concern:

Be it known that I, WILLIAM C. BURWELL, a citizen of the United States, residing at Providence, in the county of Providence and State 5 of Rhode Island, have invented and produced a new and original Design for a Ladle or Similar Article, of which the following is a specification, reference being had to the accompanying drawings, forming part thereof.

10 Figure 1 is a side view of my newly-designed ladle. Fig. 2 is a top view of the same. Fig. 3 is a sectional view of the bowl on the line X X of Fig. 1.

15 The essential feature of my design consists in the outline and configuration of the bowl of the ladle, presenting to the eye the appearance of the head of a brassay, such as is used in playing the game of golf.

20 In the drawings, A indicates the bowl of the ladle, and B the handle. The bowl has the flat base or bottom 1. The horizontal outline of the bowl A forms an imperfect oval, one of the long sides of which is straight, presenting to the eye the appearance of an oval 25 a portion of one of the long sides of which is cut away. The side 2 of the oval portion of

the bowl extends obliquely outward from the bottom, while the side 3, forming the straight portion of the bowl, extends vertically at a right angle to the bottom. The portion 4 of 30 the handle joins the bowl at an obtuse angle and tapers gradually, diminishing in diameter to the point 5, from which it extends in a curved line to the end, with the greatest diameter midway between the end and the 35 point 5.

To the eye the whole ladle presents the appearance of a brassay, an instrument used in playing the well-known game of golf.

Having thus described my invention, what 40 I claim as new, and desire to secure by Letters Patent, is—

The design for a ladle or similar article herein shown and described.

45 In testimony whereof I have signed my name to this specification in the presence of two subscribing witnesses.

WILLIAM C. BURWELL.
